(57) CLAIM

The ornamental design for a tent and fly, as shown and described.

DESCRIPTION

The drawings described below show a complete description of the design claimed. The right side view is symmetrical to the left side view of FIG. 2. The bottom view is essentially flat.

FIG. 1 is a perspective view of the tent and fly showing our new design;

FIG. 2 is a left side elevation view thereof;

FIG. 3 is a front elevation view thereof;

FIG. 4 is a rear elevation view thereof; and,

FIG. 5 is a top view thereof.
